BATHING GARMENT

Samuel Tait, Philadelphia, Pa.

Application December 21, 1934, Serial No. 758,664

7 Claims. (Cl. 2—67)

The present invention relates to a certain new and useful bathing garment or bathing garments and to certain improvements in bathing garments whereby a relatively thin and light-weight garment may be made of knitted silk plies or webbing of relatively sheer and translucent character, which, however, in the finished garment will not be revealing, but will be relatively opaque from the normal external view when actually in use.

10 The present invention further relates to other novel features as well as certain novel details of construction in silk bathing garments, all of which will appear more fully from the following detailed description.

15 One of the objects of the present invention is to form a silk bathing garment and beach apparel, which may be made in relatively light weight, which will dry fast on the body of the wearer, which will give substantial ventilation and substantial exposure to sunlight when worn on the beach, and which at the same time will not be revealing or transparent to the normal view.

With the above and other objects in view, the present invention consists of a knitted silk bathing garment formed of a plurality of plies, sheets or webs of knitted silk fabric, each sheet or ply being relatively thin and transparent, and the multiplicity of plies combined being also relatively transparent when held close to the eye with a 25 source of light on the other side, but which when viewed at a slight distance, become non-transparent and tend to give a totally opaque effect, due to the reflection of the light by the underneath ply or plies or by the silk under-layers.

30 The present invention further consists in forming the multiplicity of knitted silk plies of a relatively fine-gauge or of a relatively fine yarn or thread so as to accentuate this dual quality or characteristic of the composed layers.

35 The invention further consists of certain other novel features and details of construction which will appear more fully from the following detailed description and accompanying drawings.

40 For the purpose of illustrating the invention, there is shown in the accompanying drawings forms thereof which are at present preferred since the same have been found in practice to give satisfactory and reliable results, although 45 it is to be understood that the various instrumentalities of which the present invention consists can be variously arranged and organized and that the invention is not limited to the precise arrangement and organization of the instrumentalities as herein shown and described.

Referring to the drawings in which like reference characters indicate like parts:

Figure 1 represents a front perspective view of a garment embodying the invention as actually worn.

Figure 2 represents a rear perspective view of the same.

Figure 3 represents a rear perspective view, also showing the combination skirt and cape element worn as a skirt.

Figure 4 represents a front elevational view on a somewhat enlarged scale, of the bathing garment more or less laid out flat, with parts broken away to expose to view the successive layers.

Figure 5 represents a fragmentary section on line 5—5 of Figure 4.

Figure 6 represents a section on line 6—6 of Figure 4.

Figure 7 represents a section on line 7—7 of Figure 4.

Figure 8 represents a section on line 8—8 of Figure 4.

Figure 9 represents a front elevational view of the combination skirt and cape member with parts enlarged to show the character of the stitch.

Figure 10 represents a section on line 10—10 of Figure 9.

Figure 11 represents a section on line 11—11 of Figure 9.

Figure 12 represents a section on line 12—12 of Figure 9.

Figure 13 represents a front perspective view of the combination skirt and cape member, shown worn as a cape.

Figure 14 represents an enlarged perspective view of the top of the front opening of the combination cape and skirt member.

Figure 15 is a perspective view of the rear of the bodice portion of the garment showing a modified form of construction of one of the details.

According to the present invention, the bathing garment designated generally by the numeral 15 may be composed of a lower bifurcated trunk portion 16 and an upper bodice portion 17;—the 45 trunk portion 16 being preferably formed with two leg openings 18 and 19.

The trunk portion 16 as well as the bodice portion 17 are formed of several layers of generally similar knitted silk webs or plies of relatively fine 50 gauge. In the particular illustration here shown, the trunk and the bodice portions 16 and 17 are shown as formed of three layers or webs. The layers or webs of the trunk member are designated by the numerals 20, 21 and 22, respectively, 55

while the layers or webs of the bodice are designated by the numerals 23, 24 and 25, respectively.

The knitted silk layers 20, 21 and 22 of the trunk portion 16 are preferably arranged with 5 the courses extending horizontally and with the ribs or wales extending vertically so that the direction of greatest elasticity will be horizontally or circumferentially of the trunk.

The layers or webs 23, 24 and 25 of the bodice 10 portion are preferably arranged with the courses running vertically, and with the ribs or wales therefore running horizontally so that the direction of the greatest elasticity of these layers will be in a vertical direction rather than in a 15 horizontal or circumferential direction.

Each of the knitted silk layers, sheets, or webs 20, 21 and 22 on one hand, and 23, 24 and 25 on the other hand, are preferably formed on fine-gauge flat knitting machines, as for instance, 20 the flat type or full-fashioned machines commonly used for knitting full-fashioned or fine 25 or sheer silk hosiery. The knitted silk layers, sheets or webs 20, 21 and 22 on one hand and 23, 24 and 25 on the other hand may also be formed on a suitable fine-gauge circular knitting machine of sufficiently large diameter to give the necessary width of fabric for a bathing suit, or the necessary width for the parts or sections 30 of a bathing suit. So, too, any other type of knitting machine may be employed of sufficiently fine-gauge, to produce these knitted fabric layers or plies, as for instance "warp" type knitting machines etc.

The trunk portion may be formed of four 35 more or less equal quarterly sections dividing the circumference into four parts, or it may be formed of two parts of correspondingly greater width or correspondingly greater circumferential extent.

The drawings illustrate a form of construction 40 in which the trunk is formed of four sections, two front sections and two rear sections;—the two front sections being joined along the front vertical median line 26, while the two rear sections are joined along the rear vertical median 45 line 27, while the front and rear sections on one side are joined along the side seam 28, and the front and rear sections on the other side are joined along the side seam 29, both extending generally vertically.

The bodice portion 17 may be formed of a 50 single section (that is, each of the three plies is, in and of itself, an integral piece). In the formation of the four trunk sections 30, 31, 32 and 33, it has been found preferable to reinforce portions by automatically throwing in another yarn 55 carrier finger (by any suitable conventional pattern chain or pattern mechanism or control mechanism) over some of the needles which will knit the reinforced portions and for the number 60 of courses to be covered by the reinforced portions.

Thus, for instance, the fine-gauge knitted silk layers or webs 20, 21 and 22 on one hand, and 23, 24, and 25 on the other hand, may be knitted 65 of an eight-end silk yarn or with eight threads of silk to produce a weight of fabric more or less the same as the weight which is commonly known as "service weight" in women's silk hosiery, which will be relatively fine and relatively transparent or translucent knitted silk webbing which 70 will permit the passage of a substantial amount of light by direct transmission or passage through the multiplicity of small discrete openings in the knitted loops and which will thus give a substantial direct-exposure to light (and also to air).

If desired, additional yarn carrier, carrying an additional yarn of possibly six ends of silk (more or less), may be thrown into action or into operative position through the areas to be reinforced, so that the reinforced zones will be of an increased weight, that is, will be of a weight corresponding to a fourteen-thread silk yarn, (more or less) while the rest of the fabric layers will be of a weight corresponding to an eight-thread silk 10 yarn (more or less).

The reinforced zones are preferably duplicated through each of the plurality of layers in registration with each other.

Thus, at the front of the garment immediately above the crotch portion, reinforced zones 34 15 and 35 may be produced, while along the back seam 27, narrow marginal reinforcement zones 36 and 37 may be formed. If desired, this marginal reinforcement may also be provided adjacent to the front seam 26 and adjacent to the 20 side seams, to provide more substantial anchorage for the seaming threads so as to permit the adjacent "sections" of the garment to be joined, with their adjacent edges merely in 25 abutting relation instead of in overlapping relation to each other and yet to give substantial durability at the seams.

In the bodice of the garment, a horizontally disposed reinforced zone 38 may be provided extending substantially across the bodice of the 30 garment, and, if desired, extending substantially throughout the entire circumferential extent of the bodice of the garment from the terminal portion 39 to the terminal portion 40, and being of a vertical extent or "width" sufficiently great 35 to give adequate breast support.

The trunk portion 16 may terminate generally at the waist line 41 of the garment in a generally tubular channel formation 42 indicated particularly in the sectional view in Figure 8; the tubular channel or chamber being adapted to receive a draw-string, tape or cord, or an elastic waist-confining member 43 which is laced through the tubular portion 42, and may have its ends extending exteriorly as at 44, to be tied 45 and adjusted at will. The tubular formation 42 in the waist zone may be formed by turning back the three plies, and stitching the same by suitable zig-zag or overlapped stitches 45, which will permit the lateral stretching of the tubular 50 formation in a generally circumferential direction with respect to the wearer, without tearing the stitches. The bodice portion may be similarly stitched to the tubular formation 42 by means of the suitable zig-zag stitches 46. 55

The bodice member 17 is seamed or closed in along its free edges 47, 48 and 49 by any suitable seam such as the seam indicated particularly in Figures 5 and 6, while the upper edges 50 and 51 may be similarly seamed in as indicated particularly in Figure 7 by any suitable overlock 60 stitch or similar stitch 52, which may be formed on any conventional machine suitable for this purpose.

The straps 53 and 54 are preferably inserted 65 between the plies and sewed in place as indicated in Figures 1 and 4 and are adapted to extend over the shoulders and then to cross each other and to be fixedly or adjustably or detachably fastened to any suitable loops or other equivalent means 55 and 56 connected with the terminal portions 39 and 40 of the bodice portion of the garment (as indicated in Figure 3), or the straps 53 and 54 may be merely extended or laced through the loops 55 and 56, and then 70 75

detachably and adjustably fastened to the waist zone at opposite points at the rear, as for instance, at 57 and 58 by means of suitable loops connected to the waist zone (as indicated in Figure 15) and these loops may be either rings or merely fabric loops fastened in place. The straps 53 and 54 are preferably formed of the same material as that of which the garment is formed, and also formed of a plurality of plies 10 with the ribs or wales running longitudinally of the strap, and the courses running transversely of the straps.

If the straps 53 and 54 are fastened at 39 and 40, then an elastic connector member 59 may also 15 be interposed between the loops 55 and 56 with any suitable adjustment, as for instance, the adjustable buckle 60.

A combination skirt and cape member designated generally by the numeral 61 may be similarly formed and may be formed of three sections 62, 63 and 64, each section being formed of two or more plies 65 and 66;—the sections being joined along the vertical seams 67 and 68. The courses are preferably arranged horizontally 25 and the ribs or wales vertically. The lower edge may be folded in as at 69, and stitched as at 70, while the upper edge may also be turned in as at 71, and stitched as at 72 to provide a tubular channel or chamber 73 through which the tie string 74 may be extended.

The sections 62, 63 and 64 may be either cut to shape or may also be fashioned or narrowed (to greater or lesser extent) directly on the knitting machine. Similarly, the several sections of 35 the trunk may also be shaped or fashioned by the usual narrowing operations of the knitting machine, or they may be cut to shape, or may be both narrowed or fashioned on the knitting machine as well as cut to shape along some 40 lines. In Figure 9, the narrowing marks 75 have been indicated, although it is to be understood that these narrowing marks may be completely sealed within the seams 67 and 68 by placing the narrowing points closer to the selvage of the 45 fabric as it is knitted, so that the narrowing marks will be completely encompassed within or embraced within the seams, and thus rendered invisible.

To the free upright edges 76 and 77, fastener tapes 78 and 79 are sewn by stitches 80 and 81, said tapes carrying any conventional interlocking scoop type fastener members 82, adapted to be connected or disconnected from each other at will by the operating slide 83, of any suitable 55 or conventional construction. The fasteners are arranged for complete separation with the guides 84 and 85 arranged for initiating the connection between the fasteners. The member 61 may either be worn as a skirt, that is, auxiliary to 60 the bathing garment, as indicated particularly in Figures 1 and 3, or it may be worn as a cape as indicated in Figure 13.

One or two crotch members or crotch sections generally V-shaped or diamond shaped, as for 65 instance the crotch section 86 may be inserted in the crotch zone, seamed and fastened in place by the seams 87. These crotch members or sections are also preferably of reinforced weight of 70 multi-ply, and with the ribs extending generally horizontally and the courses vertically, as indicated particularly in Figure 4.

By the fine-gauge multi-ply bathing garment or garments of the present invention, the weight and thickness of the garment may be much reduced, the garment rendered more free to the

movements of the body and rendered more free to the penetration of air and to the direct-passage or direct-transmission of sunlight, is rendered quick-drying and is at the same time rendered non-revealing insofar as normal observation or normal point of view is concerned.

Thus, as stated above, while each of the layers of fine-gauge light-weight knitted silk fabric is more or less transparent or translucent, and while the combination of the plurality of layers of such fabric is likewise transparent or translucent when held close to the eye and permits the direct passage of light in substantial amount, it (the combination of the plurality of layers) becomes nevertheless non-revealing and gives an opaque 15 appearance when in actual use against the body of the wearer, and in fact tends to give a moiré effect or appearance by virtue of the successive reflections of the different plies of silk. Thus, as the interstices of the successive layers are generally equally spaced but generally do not register with each other exactly, there is a sufficient lack of registration to create not only an opaque effect, but also to create a moiré appearance.

The garment of the present invention has been 25 found much superior to both woolen as well as cotton bathing garments of any of the conventional or heretofore known or used constructions when viewed from any viewpoint of the swimmer or bather. Thus, by the present invention, a bathing garment may be provided which can be of minimum weight, and give maximum freedom of body movements as is desirable for actual swimming, and which will also give air and sunlight substantial access to the portions 30 of the body generally covered by the bathing garment, without however being revealing from the normal viewpoint of an observer so that the same bathing garment may also be highly desirable for beach wear by virtue of its characteristics above 35 mentioned.

The foregoing novel results of the construction of the present invention may be attributed, in a measure, or in part, to the combination of the multiplicity of more or less discreet openings 45 formed by or within the knitted loops or stitches and the relatively smooth and relatively lustrous or light-reflective filaments constituting the thread or yarn of which these loops are formed, whereby the light from without may penetrate 50 through the multiplicity of small apertures or loops in the plurality of knitted fabric layers, to the body;—and whereby any light which may tend to be reflected from the body outwardly is either intercepted by the threads or is so reflected by the threads of the successive fabric layers as to destroy or substantially to obliterate 55 all vision of the body from any normal external viewpoint.

The reinforced zones 34 and 35 of the trunk 60 part and the reinforced zone 38 of the bodice also serves to increase the non-revealing qualities of the garment in these zones.

The invention may be embodied in other specific forms without departing from the spirit or 65 essential attributes thereof, and it is therefore desired that the present embodiments be considered in all respects as illustrative and not restrictive, reference being had to the appended claims rather than to the foregoing description 70 to indicate the scope of the invention.

Having thus described my invention, what I hereby claim as new and desire to secure by Letters Patent, is:

1. A bathing garment including a trunk mem- 75

5 ber, formed substantially in its entirety of a plurality of relatively fine-gauge, light-weight and more or less light-transmissive knitted plies of relatively smooth and more or less light-reflective filaments, which (bathing garment) is generally non-revealing when generally against the body of the wearer as in actual use.

10 2. A bathing garment including a trunk member, formed substantially in its entirety of a plurality of relatively fine-gauge, light-weight and more or less light-transmissive knitted silk plies, which (bathing garment) is generally non-revealing when against the body of the wearer.

15 3. A bathing garment comprising a trunk member and a waist member each formed of a plurality of relatively fine-gauge, light-weight and more or less light-transmissive knitted plies of relatively smooth and more or less light-reflective filaments, which (bathing garment) is generally non-revealing when against the body of the wearer;—the knitted courses of the trunk layers and the knitted courses of the waist layers running in directions generally transversely of each other.

20 25 4. A bathing garment comprising a waist member formed of a plurality of relatively fine-gauge, light-weight and more or less light-transmissive knitted plies of relatively smooth and more or less light-reflective filaments, which (bathing garment) is generally non-revealing when against the body of the wearer;—said plies having generally horizontally disposed reinforced breast zones

5 in registration with each other formed of an increased number of filaments.

10 5. A bathing garment including a trunk member, formed substantially in its entirety of a plurality of relatively fine-gauge light-weight and more or less light-transmissive knitted plies of relatively smooth and more or less light-reflective filaments, which (bathing garment) is generally non-revealing when against the body of the wearer;—said garment being formed of sections and the sections being united by sewn means, and said plies having reinforced marginal zones formed of an increased number of filaments, said reinforced zones of the several plies being generally in registration with each other adjacent 15 the seam.

15 20 6. A bathing garment including a bodice member, formed substantially in its entirety of a plurality of relatively fine-gauge, light-weight and more or less light-transmissive knitted plies of relatively smooth and more or less light-reflective filaments, which (bathing garment) is generally non-revealing when generally against the body of the wearer as in actual use.

25 7. A bathing garment including a bodice member, formed substantially in its entirety of a plurality of relatively fine-gauge, light-weight and more or less light-transmissive knitted silk plies, which (bathing garment) is generally non-revealing when generally against the body of the wearer as in actual use.

30 SAMUEL TAIT.
